ABSTRACT OF THE DISCLOSURE

A toner dispenser is disclosed for use in an electrostatic printing apparatus. The dispenser member comprises a support shaft, a porous dispenser roll and an intermediate polymeric adhesive.

BACKGROUND OF THE INVENTION

This invention relates to a dispensing apparatus and more particularly to a dispenser of toner particles in an electrostatic printing apparatus.

Generally, toner dispensers for electrostatic printing machines comprise a hopper having an opening at the bottom thereof for the gravity feed of toner particles into some portion of a developing apparatus located below the opening. Actual dispensing of the toner particles is accomplished by the use of a metering device supported across the opening and arranged to be activated to an open condition periodically by control devices which are set to cause toner dispensing when required. Because of this vertical gravity feed in a hopper-type dispenser, there are occasions when toner becomes compacted and may not be dispensed or replaced in the proper manner. In order to alleviate this problem a toner dispenser has been devised wherein a roller means is utilized to dispense the toner particles to the particular developing apparatus. This dispenser generally comprises a porous, flexible roll wrapped about a shaft. Although this dispensing unit has been found useful for many purposes, certain problems have developed due to the undesirable manner in which the roll has been fixed to the shaft. Presently, a conventional glue comprising a hard protein substance, largely gelatin, is used to bond the dispenser roll to the shaft. However, this technique has been found ineffective in that it takes a considerable period of time for the glue to dry, and, in addition, the bond made between the dispenser roll and the shaft is poor and the uniformity of the seal inadequate. As the flexible cylinder is pulled onto the shaft the glue tends to collect further contributing to the inadequate seal.

Therefore, it is an object of this invention to provide a dispensing apparatus which will overcome the above-noted disadvantages.

It is a further object of this invention to provide a means for securely fixing a toner dispensing roll to the surface of a drive shaft.

It is still a further object of this invention to provide a novel toner dispenser to be used in an electrophotographic apparatus.

It is yet still a further object of this invention to provide a novel method for preparing a toner dispenser roll for an electrophotographic imaging apparatus.

The foregoing objects and others are accomplished in accordance with the present invention, generally speaking, by utilizing a polymeric adhesive to bond the dispenser roll to the drive shaft, thereby providing a uniform and effective bond between the roll and the shaft. This is achieved in a very short period of time. A thin coating of a polymeric adhesive is formed about the surface of the shaft. A porous, flexible roll or sleeve such as polyurethane foam is fitted around the coated rod so as to form a continuous roller comprising the drive or support

2

rod, a polyurethane roll about the rod and the intermediate adhesive layer. The adhesive material is then heated to its melting temperature for a time sufficient to form the desired bond between the polyurethane and the underlying support substrate. The roller configuration is then allowed to cool. The adhesive solidifies providing the necessary bond between the urethane and the substrate for application in an electrophotographic imaging apparatus.

10 The invention is further described by the accompanying drawings wherein:

FIG. 1 represents a schematic sectional view of an electrostatic printing apparatus embodying the toner dispenser of the present invention;

15 FIG. 2 is a partial sectional view of a toner dispensing mechanism for use with the developing apparatus of an electrostatic imaging machine as set out in FIG. 1; and

FIG. 3 is a cross sectional view of the toner dispenser roll of the present invention.

20 For a general understanding of the electrostatic system in which the invention may be incorporated reference is made to FIG. 1 in which various components of an electrostatic system are schematically illustrated. As in all electrostatic systems such as a xerographic machine of the

25 type illustrated, a light image of an original 1 to be reproduced is projected onto the sensitized surface of a xerographic plate 12 to form an electrostatic latent image. Thereafter, the latent image is developed with an oppositely charged developer material comprising toner particles to form a xerographic powder image corresponding to the latent image on the plate surface. The powder image is then electrostatically transferred to a support surface such as paper to which it may be fixed by a fusing device whereby the powder image is caused to permanently adhere to the support surface.

30 The electrostatic developer material commonly used comprises a pigmented resinous powder referred to as toner and a carrier of large granular beads removed in the triboelectric series from the toner so that a triboelectric charge is generated between the toner powder and the granular carrier. The toner is attracted to the electrostatic latent image from the carrier to produce a visible powder image on an insulating surface.

35 In the illustrated apparatus, an original 1 to be copied is placed upon a transparent support platen 2 arranged in an illumination assembly generally indicated by the reference numeral 10. While on the platen an illumination system flashes light rays upon the original producing image rays corresponding to the informational areas of the original. The image rays are projected by means of an optical system 11 to an exposure station A for exposing the photosensitive surface herein represented as a xerographic or photoconductive belt 12. The photoconductive belt is charged prior to reaching the exposure station by 40 a corona device 13 located at a belt run extending between support rollers 14 and 15. The exposure station extends between the roller 14 and roller 16.

45 The exposure of the belt surface to the light image discharges the photoconductive layer in the areas struck by light, thereby producing an electrostatic latent image corresponding to the projected light image of the original. As the belt surface continues its movement the electrostatic latent image passes through a developing station B located at a third run of the belt between rollers 16 and 15 at which there is positioned a developing apparatus generally designated 17. Any suitable means (not shown) such as vacuum or tensioning means may be utilized for maintaining the belt flat in all three belt runs and, in addition, the belt run related to the development zone B is maintained at an inclined plane. The developing apparatus 17 comprises a toner dispenser generally indicated

by reference numeral 18 which delivers the toner particles to the developing zone B by way of the specific development means contained in housing 26. As toner powder images are formed, additional toner particles are supplied to the chamber closed by housing 26 by the toner dispenser 18.

The developed image is next transported by the belt to a transfer station C located at a point of tangency on the belt as it moves around the roller 15. A sheet of copy paper is moved at a speed synchronous with the moving belt in order to accomplish transfer of the developed image. There is provided at the transfer station C a transfer roll 19 which is arranged on the frame of the machine for contacting the non-transfer side of each sheet of copy paper as the latter is brought into contact with the belt 12. The transfer roller 19 is electrically biased by corona roller 20 with sufficient voltage so that a developed image on the belt 12 may be electrostatically transferred to the transfer sheet S as it is brought into contact therewith. A stripping finger or air puffing device 21 is positioned to strip the sheet from the roller 19 and continues to remove the transfer sheet S by way of vacuum conveying system 22 to final discharge at station 30.

There is also provided a suitable sheet transfer mechanism adapted to transport the sheets of paper from a paper handling mechanism generally indicated by the reference numeral 23 to the transfer station C. A programming device operatively connected to the mechanism 23, stripper device 21 and the illumination system 11 is effective to present a developed image at the transfer station C in timed sequence with the arrival of a sheet of paper so that these elements function for their intended purpose.

After the sheet S supporting the transferred toner image is stripped from the belt 12 via roller 19 it is conveyed by the conveying system 22 into a fuser assembly generally indicated by the reference numeral 24 wherein the developed toner particles or powder image on the transfer sheet are permanently affixed thereto. After fusing, the finished copy is discharged from the apparatus at station 30. The toner particles remaining as residue from the developed image, background particles and those particles not otherwise transferred, are carried by the belt 12 to a cleaning apparatus 25 positioned on the run of the belt between rollers 14 and 15. The cleaning device comprises a rotating brush, a Corotron for neutralizing charges remaining on the particles and a discharge lamp for discharging any remaining electrostatic charges on the belt. The run of the belt adjacent to the cleaning device is maintained on an inclined plane relative to the horizontal, as this run leaves the uppermost roller 15. Such an arrangement maintains the relatively straight line of copy sheet movement which operatively cooperates with the printing belt 12 at its highest point.

Referring now to FIG. 2, a sectional view of the developing apparatus 17 is represented comprising the toner dispenser housing 18 and the developer housing 26. The housing 26 is substantially closed except for an opening adjacent the photoconductive belt 12 so that development of the latent image may be realized. This housing serves as a container for the developer material and the specific development mechanism utilized in the respective apparatus. In the present instance the development mechanism is represented as a magnetic development system comprising four magnetic brushes 31, 32, 33 and 34, a paddle wheel impeller 46, having a plurality of blades radially extending therefrom, and rotatably mounted within the chamber 26 by drive shaft 47. During a development cycle the impeller 46 is rotated in the direction shown by the arrow, transporting developer material to the lower surface of the magnetic brush 31. The depleted developer material which is carried beyond the magnetic brush 34 or the last brush in the chain of magnetic brushes is conveyed back into the housing 26 to be reused for development purposes, by a longitudinal plane or

baffle plate 61 via a cross mixing baffle (not shown) which controls the movement of the development material into working engagement with the paddle wheel 46 for presenting the development material to the magnetic brush cylinders.

The developer apparatus 17 comprises a dispenser housing 18 having mounted therein for rotation a developer dispenser 82 comprising a dispenser roll 83 mounted on a shaft 84. The dispenser roll is preferably formed of a porous flexible material such as polyurethane foam, silicone foam, polyethylene foam and polystyrene foam. The porous nature of the dispenser roll provides isolated areas in which toner particles may be contained during the dispensing thereof. Toner particles 86 completely surround the dispenser roll, thereby allowing the particles to become embedded in the surface thereof. The shaft 84 for the roll 83 is arranged so that the inner edge 85 of partition plate 81 extends slightly into the periphery of the roller. The periphery of this roller also similarly is engaged by the protruding edge 86 of an upturned portion of the lower wall of the housing 18. Upon rotation of the dispenser roll particles contained in the periphery thereof are flipped out by the action of the edges 85 and 86. The toner particles so dislodged are cascaded down to the developer mechanism of the developer apparatus.

Referring now to FIG. 3 there is seen a cross section of the developer dispenser 90 of the present invention comprising the dispenser roll 91, a drive shaft 92 and the intermediate adhesive layer 93. The drive shaft may be fabricated from any suitable material such as metal, as for example aluminum and steel or plastic such as Teflon, polytetrafluoroethylene. Any suitable adhesive polymer may be used as the intermediate bonding layer of the present invention. Polymeric adhesives are generally classified according to chemical composition and include thermoplastic adhesives, elastomeric adhesives, thermosetting adhesives, and alloy adhesives, the latter referring to adhesive compounds made up from resins of two or more of the previously chemical compounds, e.g. thermosetting and thermoplastic or thermosetting and elastomeric. The thermoplastic adhesives can be softened or melted by heating and hardened by cooling. They are based on thermoplastic resins dissolved in solvent or emulsified in water. Elastomeric adhesives are based on natural and synthetic rubbers, and are available as solvent dispersions and latexes, or water dispersions. They are primarily used as compounds which have been modified with resins to form some of the adhesive alloys discussed above. They are similar to the thermoplastics in that they soften with heat. Thermosetting adhesives are based on thermosetting resins that soften with heat only long enough for the cure to initiate. Once cured, they become relatively infusible up to their decomposition temperature. The alloy type adhesive refers to adhesive compounds formed from resins of two or more different chemical families as stated above. In such adhesives the performance benefits of two or more types of resins can be combined. For example, a thermosetting resin may be plasticized by a second resin resulting in improved toughness and flexibility. Typical thermoplastic adhesives include polyvinyl acetate, polyvinyl alcohol, acrylic esters, ethylene-vinyl acetate, cellulose nitrate, asphalt and oleo-resin adhesives. Typical thermosetting adhesives include phenolic, resorcinol, phenol-resorcinol, epoxy, epoxy-phenolic, urea, melamine, and alkyd resins. Elastomeric adhesives include natural rubber, reclaimed rubber, butadiene, neoprene, acrylonitrile-butadiene, and silicon. Alloy type adhesives include phenolic-polyvinyl butyral, phenolic-polyvinyl formal, phenolic-neoprene rubber, phenolic-nitrile rubber and modified epoxy.

The process of preparing the dispenser member of the present invention is preferably accomplished in reference to a sequential mode of operation wherein a thermoplastic or elastomeric type of adhesive is utilized. In this instance the adhesive is applied to the support rod, heated

to its softening temperature and then cooled to produce the adhesively coated rod. Then the polyurethane or porous dispenser roll is formed about the coated rod, heat again applied to resoften the adhesive and then the entire composite cooled to produce the final dispensing member. Although this is a preferred mode of operation, the process of preparing the developer dispenser may be carried out in a simultaneous mode of operation whereby the adhesive material and the porous dispenser roll are applied together in a layered configuration to the support rod and heat applied in a one step process. Cooling produces the dispensing member in a one-heating-step process. In this particular embodiment the thermosetting adhesives or the alloy adhesives may be found useful in addition to the thermoplastic and elastomeric adhesives. The thermoplastic or elastomeric adhesive may be applied to the shaft by any suitable technique such as preheating the adhesive material to its melting or softening temperature and rolling the rod in a metered manner through the melted material, dip coating the adhesive onto the surface of the metal rod, brushing the adhesive material onto the rod, flow coating the rod with the adhesive, or pre-forming the polymeric adhesive in the form of a sleeve, slipping the sleeve over the rod and then applying heat either directly to the adhesive or indirectly by way of the rod, when the latter is metal, in order to soften the material and establish the necessary chemical bond between the rod and the adhesive. The thickness of the coating is not considered to be critical and generally will be at least about 5 mils or greater. After the thermoplastic material or adhesive resolidifies, a sleeve or roll of the porous material, such as a polyurethane roll, may be placed over the shaft producing the composite developer dispenser set out in FIG. 3. The polymeric material is then reheated to its melting or softening temperature by any one of a number of techniques such as applying electric current through the shaft, applying direct heat to the shaft, when the shaft is metal, using a hollow red or cylinder and inserting a heating element such as a quartz heating element, induction or capacitor heating, or placing the entire configuration in an oven regulated to the softening or melting temperature of the particular adhesive. After the thermoplastic has been softened the heating environment is removed and the dispenser allowed to cool, thus producing an excellent uniform bond of a porous roll to the shaft.

Although the above discussion in many instances was very specific in terms of conditions and materials used, any of the above-listed typical materials and alternate process steps may be implemented in order to carry out the present invention. In addition to the steps used, as set out above, other steps or modifications may be implemented, if desirable. For example, the support rod may be surface treated in order to enhance its response to the adhesive material. In addition, other materials may be incorporated in the porous dispenser roll, the adhesive polymer, or the support member which will enhance, synergize or otherwise desirably effect the system of the present invention. For example, silane adhesion promoters may be added to the adhesive to increase its respective adhesive properties.

Those skilled in the art will have other modifications occur to them based on the teachings of the present invention. These modifications are intended to be encompassed within the scope of this invention.

What is claimed is:

1. A method of preparing a toner dispenser for use in an electrostatic printing apparatus comprising applying a polymeric adhesive to the surface of a plastic support rod, heating said rod to soften said adhesive such that the adhesive flows in a uniform manner over the surface of said rod so as to form a uniform coated layer thereon, cooling said uniformly coated rod, adapting about the surface of said coated rod a porous dispenser roll material selected from the group consisting of polyurethane, poly-

ethylene, polystyrene and silicone, heating the configuration to resoften said polymeric adhesive, and cooling the configuration so as to bond said dispenser roll material to said support rod.

- 5 2. A method of preparing a toner dispenser according to claim 1 wherein said porous dispenser roll comprises polyurethane.
- 10 3. A method of preparing a toner dispenser according to claim 1 wherein said polymeric adhesive is selected from at least one member of the group consisting of thermoplastic adhesives, thermosetting adhesives, elastomeric adhesives, and alloy adhesives.
- 15 4. A method of preparing a toner dispenser according to claim 1 wherein said support rod is a metallic shaft.
- 5 5. A method of preparing a toner dispenser according to claim 1 wherein said support rod is a hollow metallic cylinder and said heating steps are realized by the insertion of a heating element within the cavity of said cylinder.
- 20 6. A method of preparing a toner dispenser according to claim 5 wherein said heating steps are carried out by applying an electric current to said metallic cylinder.
- 25 7. A method of preparing a toner dispenser for use in an electrostatic printing apparatus comprising applying a polymeric adhesive to the surface of a metallic support rod, heating said rod to soften said adhesive such that the adhesive flows in a uniform manner over the surface of said rod so as to form a uniform coated layer thereon, cooling said uniformly coated rod, adapting about the surface of said coated rod a porous dispenser roll material selected from the group consisting of polyurethane, polyethylene, polystyrene and silicone, heating the configuration to resoften said polymeric adhesive, and cooling the configuration so as to bond said dispenser roll material to said support rod.
- 30 8. A method of preparing a toner dispenser according to claim 7 wherein said heating steps are carried out by applying an electric current to said metallic support rod.
- 35 9. A method of preparing a toner dispenser for use in an electrostatic printing apparatus comprising applying a thermoplastic adhesive to the surface of a metallic or plastic drive shaft, heating said drive shaft to soften said adhesive such that the adhesive flows in a uniform manner over the surface of said shaft so as to form a uniform coated layer thereon, cooling said uniformly coated shaft, adapting about the surface of said shaft a porous dispenser roll material selected from the group consisting of polyurethane, polyethylene, polystyrene and silicone, heating the configuration to resoften said adhesive, and cooling the configuration so as to bond said dispenser roll to said shaft.
- 40 10. A method of preparing a toner dispenser according to claim 9 wherein said heating steps are carried out by applying an electrical heating source to said shaft.
- 45 11. A method of preparing a toner dispenser according to claim 9 wherein said drive shaft is a hollow cylinder and said heating source is a quartz heating element which is inserted into the cavity of said cylinder during said heating steps to provide the necessary adhesive softening effect.
